(21) Appl. No.: 29/185,377

CLAIM

(22) Filed: Jun. 27, 2003

I claim the ornamental design for a selectively accessible container for gratuities, as shown and described.

DESCRIPTION

(51) LOC (7) Cl. 99-00

FIG. 1 is a top, front and right side perspective view of a selectively accessible container for gratuities showing my new design;

(52) U.S. Cl. D99/34

FIG. 2 is a front elevational view thereof;

(58) Field of Search .... D99/28, 34, 35, D99/36; 206/0.815; 232/4 R; 446/4, 8-10; 194/344, 352; 220/662; 229/162.1

FIG. 3 is a rear elevational view thereof;

(56) References Cited

FIG. 4 is a top plan view thereof;

U.S. PATENT DOCUMENTS

FIG. 5 is a bottom plan view thereof;
